SPARK PLUG STRUCTURE

Filed March 10, 1926

Patented July 30, 1929.

1,722,269

UNITED STATES PATENT OFFICE.

OLE K. BOGSTRAND, OF BROOKLYN, NEW YORK.

SPARK-PLUG STRUCTURE.

Application filed March 10, 1926. Serial No. 93,561.

My invention relates to spark plug structures for use in gasoline and other internal combustion engines employing the jump spark system of ignition.

One object of my invention is to provide a spark plug which causes sparks to occur at a plurality of points throughout the explosive mixture resulting in a more perfect combustion of the mixture with the consequent elimination of the objectionable deposits due to unburnt carbon particles.

Another object of my invention is to provide a spark plug employing a plurality of series gaps so that should one of the gaps be bridged by a carbon particle and be rendered ineffective, the other gaps would nevertheless be operative and the plug would still function.

A further object of my invention is to provide a spark plug in which the primary and secondary coils are imbedded directly in the structure of the plug itself.

Another, and important, object of my invention is to construct a spark plug having associated therewith a simple and effective means for priming the engine.

Still another object of my invention is to provide a spark plug having a plurality of gaps, in which means are provided for readily and conveniently cleaning the gaps.

Further objects of my invention will in part be apparent and will in part be pointed out in the description of the accompanying drawings, in which I have disclosed one modification of my invention. However, I do not intend to be limited to the details of construction disclosed but intend to cover all such modifications as will readily occur to one skilled in this art and as fall within the scope of the appended claims.

In the drawings:

Figure 1 is a sectional elevation view on the line 2—2 of Figure 4;

Figure 2 is a view of a part of the spark plug looking at the spark plug from the left of Figure 1;

Figure 3 is a view of a part of the spark plug looking at the spark plug from the right of Figure 1;

Figure 4 is a sectional view taken through the plane indicated by lines 3—3 of Figure 1; and

Figure 5 is a diagrammatic view illustrating certain features of the invention.

In the drawings, the numeral 1 indicates the metal casing of the plug. This casing is reamed to form a bore in which the porcelain

insulator 2 slidably fits. The porcelain insulator seats upon the projection 3 on the internal surface of the metal casing and is securely held in position by gland nut 4. A flexible washer 5 is employed to insure gas tightness. The metal casing of the plug is externally screw-threaded and screws into the metal bushing 6. The bushing 6 is inserted from the inside of the engine into a suitable hole in its casing.

The porcelain insulator is provided with a bore for the reception of the primary coil 8 and secondary coil 7 of the ignition system. Current is fed to the primary coil from the lead wire 9 through a spark intensifier 10 of well known construction. A metal flange 11 is secured to the end of the concentric coils 7 and 8, one terminal of the primary coil 8 being electrically connected thereto, the other terminal being electrically connected to the metal casing of the plug in any suitable manner and grounded through the casing of the engine. The terminal lug 12 of the feed wire for the primary is seated on the flange 11, and clamped thereon, by means of the screw 13, bushing 14 and nut 15, the bushing and nut being threaded on the screw as shown in Figure 1. The handle 16 on the end of the screw 13 enables it to be screwed into the flange 11. A metal washer 17 is preferably interposed between the nut 15 and lug 12.

One terminal of the secondary coil 7 is connected to the metal casing of the plug in any suitable manner and grounded through the engine casing. The other terminal is connected to a ring or disc 18 which serves as the first or initial electrode in the series multi-gap arrangement hereinafter described. Below the ring electrode 18 are a plurality of spaced disc electrodes 19, 20, and 21 which are provided with projecting nibs 22 to 26, serving as discharge points. The electrodes 19, 20 and 21 may be spaced apart by any suitable means, insulating washers 27, 28 and 29 being preferably employed for the purpose. The lower electrode 25 of the stacked discs is provided with a projecting hollow cylindrical portion 30, the end of which is spaced at a short distance from the horizontal electrode 31. The electrode 31 is shaped as shown in Figure 4 and is supported from the porcelain by the arms or lugs 32, 33 which are preferably integrally formed with the electrode 31 and the ends of which are embedded directly in the porcelain. Supported from the metal casing, 1, of the spark plug, but in-

sulated therefrom in any suitable manner, are the horizontal spiral electrodes 34, 35 and 36, spaced apart to form small gaps. The spiral electrodes are supported from the porcelain core and metal casing, some of the electrodes being embedded in the core and others being cemented to the casing as shown in Figure 1. The electrode 36 has a small nib 37 projecting therefrom which nib is in close proximity to the metallic gasoline cup 38, the axis of which is substantially in alignment with the axis of the spark plug.

The gasoline cup is supported in the center of the radiating arm structure, the character of which will be readily apparent from Figures 1 and 5. This structure preferably comprises three horizontally radiating arms 39, 40 and 41, arranged at angles of about 120 degrees apart. The number of arms, of course, may be varied as desired. Each arm is composed of a metallic casing which is integrally formed with the bushing 6. Within the arm 39 there is carried the two conductors 42 and 43 which are parallel to and insulated from one another as by being embedded in an insulating substance 47. The conductor 42 is connected electrically to the gasoline cup. A small electrode 44 is supported adjacent the ends of conductors 42 and 43 and is spaced therefrom to form gaps therewith. Similarly the arm 40 comprises two conductors 45 and 46, supported in the insulator 47, and an electrode 48 spaced from the ends of the conductors. Between the conductor 43 in arm 39, and conductor 45 in arm 40, there is a small gap 49. The arm 41 houses an insulator 50 in which there is embedded the conductor 51 which is spaced from the conductor 46 in arm 40 to form a gap 52. Supported by the metal casing of the arm 41 at a slight distance from the end of conductor 51 is the electrode 53 which is grounded through the metal casing of arm 41, bushing 6 and the engine casing.

45 The operation is as follows: When a current of sufficient potential is induced in the secondary 7, the series gaps break down and discharge occurs across the gaps between vertical electrodes 19, 20, 21, across the gaps formed by the spiral electrodes 34, 35, 36, from nib 37 to the gasoline cup, thence through the radiating arm structure across the gaps therein to ground through the engine.

55 It will be noticed that the sparks occur at many points and are widely distributed and the result is that combustion is very rapid and complete. Moreover, should any of the gaps be bridged by particles of carbon the spark plug would still function as the current would pass through the carbon and cause sparks at the remaining gaps in series with the short-circuited gap or gaps. Furthermore, the resulting explosion would 60 tend to burn off the deposit of carbon or oil

and restore the inoperative gap to full effectiveness.

The gas cup, 38, affords a simple means for priming the engine. This cup may be filled with gasoline by unscrewing the screw 13 and pouring the gasoline through the opening in coil 7 and the openings in the disc electrodes 19, 20, 21.

Means are provided by which the gaps between the vertically stacked electrodes 19, 20, 21, can be cleaned. The means preferably take the form of horizontal holes shown in dotted line in Figure 1 opposite to the gaps and extending through the porcelain and metal casing of the plug. A cleaning tool can be inserted through the holes to clean the surfaces of the electrodes.

The spark plug may also be cleaned by blowing off drops of oil or water or particles of carbon or dirt between the gaps. For this purpose the screw 13 is removed and the engine turned over by a starter or otherwise, so that on the compression stroke the gases will escape through the opening in the bushing 14 and carry the deposit with them. In order that it may not be necessary to entirely remove the plug 13 to blow off the deposits as above described or prime the engine, the plug is provided with a hole 13' extending partially therethru as shown in Figure 1.

By unscrewing the plug a suitable distance, the passage 13' will register simultaneously with the atmosphere and with the interior of the plug.

In assembling the above described structure the bushing 6, and parts associated therewith, comprising the radiating arms and gasoline cup, are inserted from the inside of the engine cylinder and the bushing 6 screwed into a suitable hole in the casing of the engine. The metal casing 1, which houses the porcelain core, induction coils and stacked electrodes, is then screwed into the bushing 6, from the exterior of the engine. It will be obvious that it would be possible, if desired, to use only the casing 1 and associated parts, and dispense entirely with the bushing 6 with its radiating arms. In this case the final electrode of the spiral series of gaps would be grounded to the casing 1 instead of being insulated therefrom, and the casing 1 would be screwed into the customary spark plug aperture in the engine casing.

What I claim is:

1. In a spark plug structure, a tubular bushing, a plurality of radiating arms containing spark gaps supported by said bushing and a cup supported at the axis of the radiating arms.

2. In a spark plug structure, a tubular bushing, a plurality of radiating arms containing electrodes supported by said bushing, a hollow metal casing adapted to be inserted in said bushing, a porcelain core within the casing, a plurality of spaced

spirally shaped electrodes supported by the core and the metal casing, and a cup supported beneath the spirally shaped electrodes at the axis of the radiating arms.

- 5 3. In a spark plug structure, a hollow metal casing, a porcelain core having a recess within the casing, a plurality of vertically spaced electrodes within the recess, said elec-

trodes having vertically aligning central openings, and a cup supported beneath the electrodes having vertically aligning central openings.

In testimony whereof, I have signed my name to this specification this 6th day of March, 1926.

OLE K. BOGSTRAND.
